TUBE ARRANGEMENT FOR HEAT EXCHANGERS

William M. Gaylord, Jr., Cleveland, Ohio, assignor to Union Carbide and Carbon Corporation, a corporation of New York

Application September 28, 1950, Serial No. 187,209

8 Claims. (Cl. 257—236)

1

This invention relates to heat exchangers, and more particularly to a shell and tube type having a stainless steel shell and impervious graphite tubes which are chemically resistant to practically all corrosive fluids, resistant to severe thermal shock, and have high heat transfer rates.

The shell and the tubes therein are cylindrical and have parallel axes. When speaking of shell and tube interchangers, in all cases pitch is defined as the geometric relation, arrangement or location of the tubes. Square pitch is defined as the arrangement of the tubes with their centers at the corners of squares. Triangular pitch is defined as the arrangement of the tubes with their centers at the apices of equilateral triangles. Ligament is defined as the distance between the outside peripheries of the tubes measured along a line joining their centers. The conventional arrangement of the tubes is either on a regular equilateral triangular, or on a square pitch. These arrangements require a relatively large shell to enclose a given number of tubes for a given ligament or spacing between the outside diameter of the tubes.

The main object of the present invention is to provide an advantageous specific arrangement of tubes which will permit the use of a smaller, but not necessarily minimum, size of shell for a given number of tubes and a given ligament.

According to the present invention the tubes are partly on a square pitch and partly on a triangular pitch, preferably half and half. These tubes are also preferably arranged in rings in concentric relation, those of the inner ring being on a square pitch, those of an intermediate ring arranged in equally spaced pairs equally spaced apart in their ring, the chords connecting said pairs forming the bases of equilateral triangles, the apices of said triangles being formed by tubes in another of said concentric rings, and those of the outer ring being arranged in pairs equally spaced apart and alternating with singles which form the apices of triangles having their bases in the intermediate ring. The intermediate ring has double, and the outer ring triple, the number of tubes of the inner ring. The tubes are arranged symmetrically in quadrants, in each of which quadrants a tube center of the inner ring forms with the two tube centers of the intermediate ring the apices of an equilateral triangle, and the tube centers of the outer ring subtend right angles having vertices at the tube centers of the intermediate ring, and the two farthest apart tube centers in the outer ring in the quadrant subtend a right angle having its vertex at the said tube center of the inner ring.

In the drawings:

2

Fig. 1 is a vertical cross section through a heat exchanger having tubes arranged according to the present invention; and

Fig. 2 is an enlarged diagram of one quadrant A—A of Fig. 1 showing the geometrical arrangement and angular disposition of the tubes.

The heat exchanger comprises a stainless steel shell S which encloses the group of impervious graphite tubes indicated generally at T. The shell S has headers H at each end having apertures receiving the respective tubes, so that the headers and tubes contain one of the fluids to be treated. The headers are secured to each other by stay bolts or tie rods R. The other fluid is contained in the space inside the shell and outside of the tubes, which communicates through apertures E with a manifold M having an inlet or outlet connection C.

The grouping of the tubes T is best shown in Fig. 2. The tubes 10, 14 and 16 have their axes located at the apices of an equilateral triangle. The tubes 14, 15 and 16 are located at the apices of another equilateral triangle. Thus the four tubes 10, 14, 15 and 16 are all on a triangular pitch. The tubes 10 and 12 have their axes in a line parallel to a vertical diameter, and the tubes 10 and 17 have their axes in a line parallel to a horizontal diameter. Also the grouping is symmetrical about both diameters. Hence the tubes 30 10, 12 and 17 are on a square pitch.

With respect to the line determined by the tubes 10 and 12, the tubes 14 are located at an angle of 15° to this line. Thus the tubes 10 and 12 form a row, in which each tube is at an angle of 15° from an adjacent tube 14 farther from the diameter.

It will be noted that the four tubes 10 determine an inner ring G, the eight tubes 14 and 15 determine an intermediate ring J, and the twelve tubes 12, 15 and 17 determine an outer ring K. Thus the intermediate ring has double, and the outer ring triple, the number of tubes within the inner ring. The tubes 10 of the inner ring are on a square pitch, and the tubes 14 and 16 of the intermediate ring are on a triangular pitch. As to the outer ring, the tubes 12 of adjacent quadrants form a pair, and the tubes 17 of adjacent quadrants form another pair, both pairs being on a square pitch. In this outer ring, the pairs 50 12, 12 and 17, 17 on a square pitch alternate with singles 15 on a triangular pitch.

In the inner ring, the tubes 10 are 90° apart. In the intermediate ring, the tubes 14 and 16 are 60° apart, in the sense that the arc of the ring 55 J between the centers of these tubes 14 and 16 subtends an angle of 60° having its vertex at the center of tube 10. Similarly the centers of the

tubes 14 and 16 determine an angle of 60° having its vertex at the center of tube 15. In the outer ring, the tubes 12 and 15 are 90° apart, as are the tubes 15 and 17, in the sense that the arc of ring K between the centers of tubes 12 and 15 subtends an angle of 90° having its vertex at the center of tube 14, and the arc of ring K between the centers of tubes 15 and 17 subtends an angle of 90° having its vertex at the center of tube 16.

In the specific embodiment shown for example, there are twenty-four impervious graphite tubes all of one and one-quarter inch outside diameter, and seven eights of an inch inside diameter. The ligaments or spacing between tubes is three eights of an inch from one outside tube periphery to the next measured along a line joining their centers. The inside radius B of the shell is five inches, while all of the tubes lie within a circle of a radius D of 4.66 inches. This tube circle radius D for a rectangular pitch would be 4.875 inches, while for a triangular pitch it would be 4.687 inches.

I claim:

1. In a heat exchanger, a shell and tubes arranged within said shell in axially parallel relation and in spaced relation to each other and to the shell, said tubes being arranged with their centers in rings in concentric relation, the tube centers of one of said rings being arranged in equally spaced pairs equally spaced apart in their ring and the hypothetical chords between the tube centers of said pairs forming the bases of equilateral triangles, the apices of said triangles being formed by tube centers in another of said concentric rings.

2. In a heat exchanger, a shell and tubes arranged within said shell in axially parallel relation and in spaced relation to each other and to the shell, the centers of said tubes being arranged in rings in concentric relation, the tube centers of a smaller of said rings forming the apices of respective equilateral triangles, and the tube centers of a larger of said rings being arranged in equally spaced pairs equally spaced apart and the hypothetical chords between the tube centers of said pairs forming the bases of said triangles.

3. In a heat exchanger, a shell and tubes arranged within the shell in axially parallel relation and in spaced relation to each other and to the shell, the centers of said tubes being arranged in rings in concentric relation, the tube centers of an intermediate ring being arranged in equally spaced pairs equally spaced apart in their ring, the hypothetical chords between the tube centers of said pairs forming the bases of respective equilateral triangles, the apices of which triangles are at the centers of single tubes which alternate with equally spaced pairs of tube centers in an outer ring.

4. In a heat exchanger, a shell and tubes arranged within said shell in axially parallel relation and in spaced relation to each other and to the shell, the centers of said tubes being arranged in rings in concentric relation, the tube centers of the intermediate ring being arranged in equally spaced pairs equally spaced apart in their ring and the hypothetical chord between the tube centers of said pairs forming the bases of equilateral triangles, certain of said triangles being within said intermediate ring and having their apices at centers of the tubes of the inner ring, others of said triangles extending outside of said intermediate ring and having their apices at the centers of tubes in the outer ring.

5. In a heat exchanger, a shell and tubes arranged within the shell in axially parallel relation and in spaced relation to each other and to the shell, the centers of said tubes being arranged in rings in concentric relation and in symmetrical quadrants, in each of which quadrants a central tube center in the outer ring forms with the tube centers on each side thereof equally spaced adjacent pairs which subtend right angles having their vertices at respective tube centers in the intermediate ring, and said tube centers on each side thereof in said outer ring subtend a right angle having its vertex at a tube center in the inner ring in said quadrant.
- 10 6. In a heat exchanger, a shell and tubes arranged within the shell in axially parallel relation and in spaced relation to each other and to the shell, the centers of said tubes being arranged in rings in concentric relation, the tube centers 20 of an intermediate ring being arranged in equally spaced pairs equally spaced apart in their ring and the hypothetical chord between the tube centers of said pairs forming bases of respective equilateral triangles the apices of which are formed by tube centers in the outer ring which together with the tube centers on each side thereof in their ring form adjacent equally spaced pairs which each subtend a right angle having its vertex at a tube center of said intermediate ring.
- 25 7. In a heat exchanger, a shell and tubes arranged within the shell in axially parallel relation and in spaced relation to each other and to the shell, the centers of said tubes being arranged in rings in concentric relation and in symmetrical 30 quadrants, in each of which quadrants a tube center of the inner ring forms with two tube centers of the intermediate ring the apices of an equilateral triangle, and the tube centers of the outer ring subtend right angles having vertices 35 at the tube centers of the intermediate ring, and the two farthest apart tube centers in the outer ring in the quadrant subtend a right angle having its vertex at the said tube center of the inner ring.
- 40 8. In a heat exchanger, a shell and tubes arranged within the shell in axially parallel relation and in spaced relation to each other and to the shell, the centers of said tubes being arranged in rings in concentric relation and in symmetrical 45 quadrants, in each of which quadrants the hypothetical chord between a pair of tube centers of the intermediate ring form the common base for two equilateral triangles, one of which lies within said intermediate ring and has its apex at the tube center of the inner ring within its quadrant and the other of which triangles extends outside of said intermediate ring and has its apex at a tube center in said outer ring, said outer ring tube center and the tube centers on each side thereof in said outer ring forming pairs which 50 subtend right angles having their vertices at said tube centers of the intermediate ring, and said tube centers on each side thereof in said outer ring subtending a right angle having its vertex 55 at said tube center of the inner ring within said quadrant.
